ARCHIBALD BARR, WILLIAM STROUD, AND CHARLES DALRYMPLE MACGILL, OF GLASGOW, SCOTLAND, ASSIGNEES TO BARR AND STROUD LIMITED, OF GLASGOW, SCOTLAND.

RANGE FINDER, HEIGHT FINDER, AND THE LIKE.

Application filed July 14, 1927, Serial No. 205,716, and in Great Britain July 16, 1926.

This invention refers to rangefinders, heightfinders and like optical instruments, hereinafter and in the claims referred to generally as rangefinders, of the type which are movable angularly so as to enable observations to be made, for example, upon aircraft at any angle of sight, and which have what will be termed a working head movable with the rangefinder, the working head being rotatable for actuating means in the optical system of the rangefinder for effecting measurement of angle.

The object of this invention is to provide mechanism for rotating the working head of a rangefinder of this type, comprising a rotatable operating head, relatively to which the rangefinder is movable angularly, and differential gear to which motion due to angular movement of the rangefinder relatively to the operating head is imparted without causing relative rotation of the operating and working heads.

The means in the optical system of rangefinders to which this invention refers for effecting measurement of angle, may consist of a prism or prisms which by operation of the working head are movable longitudinally, rotationally or otherwise, say, angularly, and the invention is for rangefinders of the type for which a mounting is provided, the rangefinder, say of the self contained base type, being arranged with its base horizontal and movable angularly on the mounting about a horizontal axis for elevation and movable with the mounting about a vertical axis for azimuthal training. With a rangefinder so mounted in accordance with this invention the operating head is placed upon the mounting so as to be movable only in azimuth therewith, and, relatively to the operating head, the rangefinder and with it the working head, are rotatable for elevation about the horizontal axis, and the mechanism provided operates so that movements of the rangefinder which are imparted for elevation do not cause relative rotation of the operating and working heads, and thus do not affect the motion in process of transmission from the operating head to the working head.

Some examples of mechanism according to this invention applied to a rangefinder of the self contained base type will now be de-

scribed with reference to the accompanying drawings, in which:

Figure 1 is a sectional elevation and Figure 2 is a sectional view of a detail showing one example.

Figures 3 and 4 are sectional elevations showing modifications.

The drawings show a part say, the middle portion, of a rangefinder A, a mounting B for the rangefinder, the rangefinder being movable angularly on the mounting about a horizontal axis, which is the longitudinal axis of the tubular casing of the rangefinder A, a handle 2 for moving the rangefinder A angularly for elevation about the horizontal axis, an element C constituting the working head on the rangefinder, and an operating head D on the mounting B.

Figures 1 and 2 show a circular toothed rack 3 concentric with the longitudinal axis of the rangefinder A and fixed to mounting B, a shaft C constituting the working head movable with the rangefinder, a spindle 4 rotatable with shaft C, a gear wheel 5 rotatable on shaft C and in mesh with rack 3, a gear wheel 6 rotatable with 5, a gear wheel 7 in mesh with 6, rotatable on spindle 4, a gear wheel 8 rotatable on shaft C, and in mesh with wheel 7, a gear wheel 9 rotatable with 8, a ring E rotatable about rangefinder A, a toothed rack 10 on ring E in mesh with wheel 9, a gear wheel 12 rotatable with operating head D, a toothed rack 11 on ring E in mesh with wheel 12. The gear ratio between 3 and 5 is the same as that between 10 and 9. In this example, Figures 1 and 2, the elements 6, 7 and 8 constitute a differential gear, the principal axis of which is the axis of shaft C. The optical system of the rangefinder may have means for effecting measurement of angle similar to that shown in Figures 3 and 4, consisting of a refracting prism F movable longitudinally by mechanism comprising a gear wheel 13 rotatable with shaft C, a gear wheel 14 in mesh with 13, a screw 15 rotatable with 14, and a carrier 16 for prism F movable longitudinally by screw 15.

The description of Figures 1 and 2 applies also to Figure 3.

In operation of the mechanisms, Figures 1 and 2 and Figure 3, with D held against rotation, angular movement of rangefinder A by handle 2 causes 5 to be rotated by 3, and

9 to be rotated by 10, whereby 6 and 8 are rotated in opposite directions, and 7 is rotated on spindle 4 without causing spindle C to be rotated.

5. Figure 4 shows a segmental rack 17 fixed to and concentric with rangefinder A, a spindle 18 fixed to mounting B, a shaft 19 on mounting B rotatable with operating head D, a spindle 20 rotatable with shaft 19, a gear 21 in mesh with 17 and a gear 22 rotatable with 21, both on spindle 18, a gear 23 rotatable on shaft 19 and in mesh with gear 22, a gear 24 rotatable with 23, a gear 25 rotatable on spindle 20 and in mesh with 24, a gear 26 rotatable on shaft 19 and in mesh with 25, a gear 27 rotatable with 26. Ring H rotatable about rangefinder A, a rack 28 on ring H in mesh with 27, a gear 29 rotatable with shaft C, and a rack 30 on ring H in mesh with 29.

10. In this example, Figure 4, the elements 24, 25 and 26 constitute a differential gear, the principal axis of which is the axis of shaft 19, and the gearing between 17 and 28 is 15 such that with D held against rotation, motion imparted by 17 is equal to motion transmitted to 28. Thus with operating head D held so as not to rotate, angular movement of rangefinder A about its horizontal axis by 20 handle 2 causes 17 to rotate 21, and thereby causes 22, 23, 24, 25 (on spindle 20 which is held stationary), 26 and 27 to rotate, 27 operating to so rotate ring H, that as gear 29, in mesh with rack 30, moves angularly 25 with the rangefinder, gear 29 and its shaft C which constitutes the working head are not rotated.

35. We claim:—

1. A rangefinder, a mounting for the 40 rangefinder, the rangefinder being movable angularly for elevation relatively to the mounting, a rotatable working head movable with the rangefinder and thus angularly 45 relatively to the mounting, a rotatable operating head on the mounting relatively to which the rangefinder and working head are movable angularly, mechanism between the operating head and the working head for imparting rotational motion from the operating head to the working head, said mechanism comprising differential gear to elements of which motion due to angular movements of the rangefinder is imparted with-

55. out causing relative rotation of the operating and working heads.

2. A rangefinder, a mounting for the 60 rangefinder, the rangefinder being movable angularly for elevation relatively to the mounting, a rotatable working head movable with the rangefinder and thus angularly 65 relatively to the mounting, a rotatable operating head on the mounting relatively to which the rangefinder and working head are movable angularly, mechanism between the operating head and the working head 70 for imparting rotational motion from the operating head to the working head, said mechanism comprising differential gear to elements of which motion due to angular movements of the rangefinder is imparted 75 without causing relative rotation of the operating and working heads, the principal axis of said differential gear being not movable angularly with the rangefinder.

3. A rangefinder, a mounting for the 80 rangefinder, the rangefinder being movable about its longitudinal axis on the mounting for elevation and movable with the mounting for azimuthal training, a handle for moving the rangefinder for elevation, a 85 working head element on the rangefinder, an operating head on the mounting, a first segmental rack concentric with and movable with the rangefinder, a first spindle fixed to the mounting, a shaft on the mounting rotatable with the operating head, a second spindle rotatable with the shaft, a first gear in mesh with the first rack and a second gear 90 rotatable with the first gear, both on the first spindle, a third gear rotatable on the shaft 95 and in mesh with the second gear, a fourth gear rotatable with the third gear, a fifth gear rotatable on the second spindle and in mesh with the fourth gear, a sixth gear rotatable on the shaft and in mesh with the 100 fifth gear, a seventh gear rotatable with the sixth gear, a ring rotatable about the rangefinder, a second rack on the ring in mesh with the seventh gear, an eighth gear rotatable with the working head element, and a third rack on the ring in mesh with the eighth gear, for the purposes set forth.

ARCHIBALD BARR.
